[57] ABSTRACT

This invention relates to a novel elongate replaceable wear blade suitable for use with snowmobile suspensions of the type having a longitudinally extending skid adapted to resiliently apply to the ground engaging portion of the snowmobile's track at least a portion of the vehicle's weight. The blade is formed from a hard, wear resistant synthetic resin and has along one side thereof an elongate restricted channel opening. The channel is adapted to be slidably engaged and retained by complementary means on the skid. Abutment means are provided on the skids to hold the blades in a fixed position relative to the skids.

WEAR BLADE FOR SNOWMOBILE SKID SUSPENSION

SUMMARY OF THE INVENTION

U.S. Pat. No. 3,658,392, Perreault et al. assigned to Bombardier Limited of Valcourt, Quebec, Canada, relates to an improved tracked vehicle suspension and discloses a suspension system wherein the skids or skid members are formed from elongate box shaped channels to which wear blades are attached to the underside thereof by means of rivets. In use, it has been found that the wear blades can become worn to a sufficient degree that their replacement is required. When the snowmobile is used in mud-snow or ice conditions, sand or the like abrades the blade as the endless track continuously rotates. Further, normal wear attributable to the frictional contact between the wear blades and the metal cleats positioned between the drive sprocket holes in the endless track or other metallic members of the track is increased when the track is rotated at high speeds for prolonged periods of time or where the suspension system is subjected to rough treatment as is the case in racing. Furthermore, in certain skid systems excessive wear is encountered near the extremities of the wear blades as the endless track and its accompanying cleats are free to flex prior to the rotating tracks introduction to the blades and just after the track leaves the blades. Such systems, of course, are more likely to require frequent wear blade replacement.

Heretofore, blades which were worn required a complete dismantling of the suspension assembly from the vehicle chassis. Rivets, mounting bolts and the like had to be removed with the worn blade and then replaced with the new blades. This blade exchange required considerable time and in the majority of cases, could not be done by the snowmobile owner or enthusiast himself. In endurance racing, time lost in a pit stop for blade replacement weighed heavily in the outcome of the race.

The foregoing disadvantages have been overcome by a novel "quick change" wear blade. Essentially, the blade is made from a hard, wear resistant synthetic plastic, such as ultra high density polyethylene, polyurethane, nylon or Teflon (trade mark) and is provided with an elongate channel or slot having a restricted opening running its full length. The channel is slidably engageable with complementary retaining means on the underside of the skid and held in position by an abutment or other suitable locking means preferably provided on the trailing end of the skid. Although the replaceable wear blade hereinafter to be described in detail may be advantageously used on varying types of slide or skid suspension systems, it has particular adaptation to articulated skid suspensions wherein each skid includes two skid elements arranged in an end-to-end relationship and preferably pivotally connected to one another.

While the blade and channel may be of any desired cross-section, a rectangular blade is preferred just as is an inverted T-shaped channel. A blade of circular cross-section can, in certain snow conditions, minimize the frictional contact between the blade and metal cleats on the track. The inverted T-channelled blade is suitable with skids or skid members which have a I-shaped cross-section. The blade can be slid along the lower portion of the I-skid while the upper portion is free to serve as a retaining means which permits the

longitudinal movement of runners therealong. Runners as disclosed in U.S. Pat. No. 3,658,392 aforesaid serve to pivotally and slidably connect downwardly biased trailing arms on the chassis to the skids or skid members. The runner is provided with a channel complementing the upper retaining portion of the skid and preferably is formed from the same material as the blade. For lightness, the skids or skid members are advantageously made from extruded aluminum.

BRIEF DESCRIPTION OF THE DRAWINGS

In the accompanying drawings which illustrate embodiments of the invention:

FIG. 1 is a side view of a snowmobile suspension illustrating the novel quick change blade mounted on two skid elements,

FIG. 2 is a cross-section of the skid element, blade and track taken along lines II — II of FIG. 1,

FIG. 3 is a similar cross-section as FIG. 2 but taken along line III — III of FIG. 1 which illustrates the locking means for retaining the blade on the skid element:

FIG. 4 is a cross-section taken along IV — IV of FIG. 1 showing the stop element used on the rear skid,

FIG. 5 is a cross-section of a blade and skid illustrating a different form of skid and blade channel, and

FIG. 6 is a section similar to FIG. 5 illustrating a further blade configuration and including a runner mounted on the top portion of the skid.

DETAILED DESCRIPTION

The skid suspension shown in FIG. 1 is similar to that disclosed in U.S. Pat. No. 3,658,392 although only one side of the suspension has been shown. The suspension illustrated comprises two parallel skids, each skid having two skid elements 1 and 2 pivotally connected in end-to-end relationship for articulation. Endless track 3 is entrained about drive and idle sprockets (not shown). Metal cleats 4 positioned between the sprocket holes of the track contact blade 5 on front skid element 1 and blade 6 on rear skid element 2.

Four trailing arms 7 are pivotally connected to the snowmobile chassis (not shown) in a conventional manner and extend downwardly and rearwardly to form a pivotal connection with the skids. Pivot pins 8 at the lower extremities of arms 7 afford the pivotal connection with the skids. In FIG. 1, the rear three trailing arms 7 are also constrained for longitudinal movement relative to the skid elements by being connected thereto by means of runners 9 discussed in greater detail below. The front or leading trailing arm 7 is directly pivotally connected to the skid element 1 by means of a mount or cross-bracer 24 welded thereto. Springs 10 function to bias arms 7 downwardly and forwardly in a conventional manner.

Each skid, which may comprise two skid elements 1 and 2 as illustrated or just one continuous rail the length of which is slightly less than that of the ground engaging portion of the endless track, is preferably formed from extruded aluminum having an I-shaped cross-section. As best seen in FIG. 2 and 3, skid element 1 receivingly retains blade 5 which is provided with a complimentary channel or slot. Other skid configurations are possible, as evidenced by the "dumbbell" cross-section of the skid 11 shown in FIGS. 5 and 6. Blade 12 illustrated in FIG. 5 is rectangular in cross-section but is provided with a C-shaped channel to compliment the lower portion of skid 11. The blade 13

of FIG. 6 on the other hand has a C-shaped channel but is cylindrical in cross-section. This latter configuration in certain conditions minimizes the frictional contact between the blade and cleats 14 against which it bears.

Referring now particularly to FIGS. 3 and 4, the rear of front or leading skid 1 is provided with locks 15 which serve the two fold purpose of retaining blade 5 in position and pivotally connecting the front skid element 1 to rear skid element 2. Each lock is provided with a front outwardly projecting flange 16 which abuts the front portion of a notch 17 provided in blade 5 in order to stop the blade from moving rearwardly. The locks are held in position by bolt means 18', the bolt extending through skid 1. The trailing ends of each of the locks are also provided with a further hole for pivot pin 18 used for connecting the front skid element to the rear element. The locks effectively form "cheek plates" which receivably engage for pivotal action a central projection provided on the forward portion of rear skid element 2. Locks 15 may also serve to restrict the forward displacement of blade 6 on rear element 2. In an alternative embodiment, locks 15 can be positioned above blades 5 and 6 so as to function solely as a coupling means for articulated skids 1 and 2. In such a case, the front blade 5 can be held in position by means of a transverse pin (not shown).

The trailing portion of rear skid element 2 is provided with transverse abutment flanges 19 which effectively stop the rearward displacement of blade 6 mounted thereon.

In the articulated suspension illustrated, blades 5 and 6 are readily removed and replaced in the following manner. Pin 18 is removed and rear skid 2 displaced downwardly slightly from skid 1 thereby facilitating the forward sliding withdrawal of blade 6. Bolt means 17 and locks 15 are removed from element 1 and blade 5 withdrawn rearwardly. As a tight sliding connection between the blades and skids is preferred, a mallet may be necessary to effect removal and replacement of the blades. This is particularly true with respect to the front blade as it is necessary to upwardly deform the forward portion of it in order to have it take up the upward configuration of skid 1. Depending upon the radius of curvature of the upward curvature of the front blade (and the rear blade if it is upwardly curved as disclosed in Application Ser. No. 095,051, filed in Canada on Oct. 7, 1970), the curving action of the blade can be eased by slotting or providing the blades with V-shaped transverse cuts as shown at 30. In the embodiment illustrated, the front and rear replacement blades are inserted merely by reversing the above procedure.

The runners 9 illustrated in FIGS. 1 and 6 each include a shoe 20 provided with a slot or channel complementing the retaining means on the particular cross-section of the skid employed. Advantageously, the shoe is formed from the same material as the blade and includes the same channel cross-section as the blade. Fixedly mounted on the upper surface of shoe 20 is U-shaped member 21 provided with holes 22 for pivotally connecting the runners 9 to the trailing arms 7 by means of pivot pins 8.

As the majority of snowmobiles are designed for for-

ward progression only, it will be seen that the track, rotating in a counter-clockwise direction viewed in FIG. 1, forces blades 5 and 6 rearwardly. If the snowmobile is provided with a reverse, then the rear portion of the blades can be provided with inclined tips similar to tip 23 on blade 6. While it is not necessary to provide a stop or abutment on forward skid 1 due to the binding action of blade 5 thereon, suitable abutment means can also be provided at the forward end thereof. It is also desirable, in practice, to use skids or skid elements which are of identical length so that identically constructed replacement wear blades can be used throughout the suspension assembly.

What I claim as my invention is:

1. In a snowmobile suspension having a pair of spaced parallel elongate skids supported for sliding engagement against the ground-engaging portion of a track belt, each skid comprising a front skid section and a rear skid section pivotally interconnected, the improvement that each said skid section has a lower portion defining transversely projecting flanges and of constant cross-section throughout its length said lower portion being received in a replaceable wear blade of constant cross-section having a longitudinal restricted channel opening of a shape complementary to the cross-section of the lower portion of said skid section, releasable abutment means located at the pivotal interconnection of said front and rear skid sections, further abutment means at the rear end of said rear skid section, said abutment means being operative to prevent sliding disengagement the wear blades rearwardly from the corresponding front and rear skid sections respectively, said releasable abutment means being disengageable to permit rearwards sliding withdrawal of the wear blade of the front skid section, and forwards sliding withdrawal of the wear blade of the rear skid section.

2. A snowmobile suspension as claimed in claim 1, wherein said skids have an I-shaped cross-section.

3. A snowmobile suspension as claimed in claim 1, wherein said skids are formed from extruded aluminum and said replaceable wear blades are formed from a hard, wear resistant synthetic resin.

4. A snowmobile suspension as claimed in claim 1 wherein each front skid section has an upwardly curved forward end portion, the forward end portion of the corresponding wear blade having a number of spaced transverse notches opening from its upper side, to facilitate bending of the wear blade to conform to the upward curvature of the forward end portion of the front skid section.

5. A snowmobile suspension as claimed in claim 1 wherein said front and rear skid sections are of I-shaped cross-section each having a vertical web, and wherein said releasable abutment means comprises a pair of abutment plates arranged at the rear of each front skid section on opposite sides of the web thereof and releasably secured thereto by fastener means, said abutment plates extending rearwardly of the front skid section and defining means for pivotal interconnection of the latter to the corresponding rear skid section.
